CLOCK CASING

Ellsworth R. Danz, La Salle, Ill., assignor to General
Time Corporation, Stamford, Conn., a corporation
of Delaware

Filed Aug. 24, 1967, Ser. No. 8,375

Term of patent 14 years

(Cl. D42—7)

FIG. 1

FIG.3

FIG.2

FIG. 1 is a front elevational view of a clock casing showing my new design;

FIG. 2 is a rear elevational view; and

FIG. 3 is a left side elevational view.

The broken line showings are for illustrative purposes only.

I claim:

The ornamental design for a clock casing, substantially as shown and described.
